UNITED STATES PATENT OFFICE.

JOHN E. KILBURN, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

CAR-SEAT.

1,196,871.

Specification of Letters Patent.

Patented Sept. 5, 1916.

Application filed January 24, 1913. Serial No. 743,835.

To all whom it may concern:

Be it known that I, JOHN E. KILBURN, a citizen of the United States, residing at Philadelphia, in the county of Philadelphia 5 and State of Pennsylvania, have invented certain new and useful Improvements in Car-Seats, of which the following is a specification.

This invention relates to car-seats and is 10 directed to the provision of improved means for supporting the end of a car-seat adjacent to the side wall of the car.

The invention may be employed in seats of various types, but it is of special utility 15 in seats of the character in which the back is not arranged for movement from one edge of the seat-cushion to the other in order to reverse the facing direction of the seat.

20 Railway cars are sometimes so constructed that a projecting portion on the inner side of the wall of the car requires that the back of the seat be of such length that its edge is displaced a short distance from the wall 25 of the car, but it is desirable to have the seat-cushion extend close to the the wall of the car, so as to give the maximum seating area. These requirements may be fulfilled 30 by having the seat-cushion extend beyond the edge of the back-cushion. For the support of seat- and back-cushions of this character, a standard may be employed consisting of a horizontally disposed arm and a back-supporting arm integral therewith and 35 extending upwardly from the rear end of the horizontal arm. With such a standard, the seat-cushion may be supported upon the horizontal arm with its end extending beyond the same and the back-supporting arm 40 will extend upwardly in rear of the seat-cushion and be fastened to the edge of the back-cushion. Such a standard may also be employed at the aisle end of the seat, and there may be supported upon a suitable 45 pedestal, but at the wall end of the seat it is preferable to mount the standard upon the wall of the car.

The present invention involves the provision of a seat of this character having 50 the standard supported upon the wall of the car, and further involves the provision of an improved form of support which may be manufactured at low cost and with which the standard may be secured to the wall of 55 the car so rigidly that the possibility of

breakage or loosening of the parts is reduced to a minimum.

The preferred embodiment of the invention is illustrated in the accompanying drawings, in which—

60 Figure 1 is a front view of a car-seat constructed in accordance with the invention; Fig. 2 is an elevation of the supporting member; and Figs. 3 and 4 are top and end views of the same.

65 Referring to these drawings, the seat shown in Fig. 1 has a seat-cushion 5 and back-cushion 6, the latter being stationarily mounted at the rear edge of the seat-cushion. At the aisle end of the seat is a standard 7, preferably made of sheet-metal and consisting of a horizontally disposed cushion-supporting arm, and at the rear end thereof an integral upwardly-extending back-supporting arm 8. The horizontal 70 arm of the standard has an inclined integral flange at its upper edge, upon which the seat-cushion 5 is sustained. This standard 7 is secured to the ends of two connecting-rails 9, which are secured upon the ends 75 of the arms of a metallic pedestal 10. At the wall end of the seat, a similar standard is employed, having a horizontal cushion-supporting arm 7 and a back-supporting arm 8 integral with the arm 7 and extending 80 upwardly from the rear end thereof. The arm 8 is secured to the adjacent edge of the back-cushion 6 and lies in rear of the seat-cushion 5. The seat-cushion extends 85 beyond the edge of the back-cushion, and beyond the horizontal arm of the standard 7, so that the maximum seating area is provided upon the cushion 5, even though the structure of the car is such as to limit the length of the back-cushion 6 by requiring 90 that the edge of the back-cushion be displaced from the wall of the car.

95 The standard 7 at the wall end of the seat is mounted upon the wall of the car by means of a metallic supporting member constructed as shown in Figs. 2, 3 and 4. This metallic member is made from a piece of sheet-metal, preferably steel, which is cut to the required configuration and then pressed into the form shown in the drawings. As so 100 constructed, the supporting member has a horizontal portion 11, and at opposite edges thereof vertical portions 12 and 13, the former extending downwardly and the latter upwardly at a right angle to the hori- 105 110

zontal portion 11. Each of these vertical portions is braced upon the horizontal portion 11 by gussets 14, which hold the different portions of the supporting member rigidly in the proper relation. The horizontal member 11 is extended so as to facilitate securing the member to the wall of the car, by providing integral ears 15 which are cut from the metal of the downwardly extending member 12, as is shown in Fig. 2. 10 These ears 15, after being cut, are bent at a right angle to the member 12, so that they lie in the same plane with the horizontally disposed portion 11, as is best shown in Fig. 4. 15 The supporting member constructed as thus described is mounted upon the truss-plank 16 of the side wall of the car at the corner thereof, by bringing the ears 15 down upon the horizontal surface and the vertical portion 12 of the member against the vertical side, openings being provided in both of these portions for screws by which the member may be secured rigidly in position. The upwardly extending portion 13 of the member is riveted to the horizontal arm of the standard 7, as shown in Fig. 1. In this way, the wall end of the seat is rigidly mounted upon the side wall of the car in a manner affording great strength. The supporting member used in so mounting the seat can be made at very low cost by pressing the same from a single piece of sheet-metal. This method of supporting the wall end of the seat, furthermore, permits of making the seat-cushion of maximum length, in order to obtain the greatest seating area.

Having now described my invention, what I claim as new therein and desire to secure by Letters Patent is as follows:— 40

1. In a car seat, the combination of the

supporting wall structure having a horizontal ledge, a seat structure to be supported in offset relation from the wall structure and means for supporting the wall-end of the seat structure, consisting of a metal member having a horizontal web and vertical webs extending upwardly and downwardly from opposite edges thereof, the lower of said vertical webs being secured to the wall structure below the ledge and the upper to the seat structure, and integral ears cut from the metal of the lower vertical web and bent into alignment with the horizontal web and secured to said horizontal ledge, substantially as set forth. 45 50 55

2. The combination of the supporting wall structure, a sheet-metal member having a horizontal web and integral vertical webs extending upwardly and downwardly from opposite edges thereof, one of said webs being secured to the wall structure and the other to the seat structure, integral ears cut from the metal of one of said vertical webs and bent into the plane of the horizontal web and secured to the supporting structure, a standard secured to said upwardly extending web and having a horizontal arm and an integral back-supporting arm extending upwardly from the rear end of such arm, 60 65 and a seat-cushion supported on said horizontal arm with its end extending beyond the same and beyond said member and in front of the back-supporting arm, substantially as set forth. 70 75

This specification signed and witnessed this 21st day of January, 1913.

JOHN E. KILBURN.
